UNITED STATES PATENT OFFICE.

GIDEON R. IBACH, OF ALLENTOWN, PENNSYLVANIA.

INTERNAL-COMBUSTION ENGINE.

1,086,180.

Specification of Letters Patent.

Patented Feb. 3, 1914.

Application filed April 3, 1913. Serial No. 758,672.

To all whom it may concern:

Be it known that I, GIDEON R. IBACH, a citizen of the United States, residing at Allentown, in the county of Lehigh and 5 State of Pennsylvania, have invented an Internal-Combustion Engine, of which the following is a full and complete specification.

My invention relates more especially to that particular class of internal combustion 10 engines used in motor vehicles, and in which a plurality of cylinders are employed and the several pistons connected to a crank-shaft common to all, the connections being such that the power is applied to the shaft 15 from the pistons successively. In the construction of engines of this character it is customary to arrange the cylinders in parallel series or radially, and usually in pairs, the number being determined according to 20 the size of the vehicle and power required to drive it.

In the present instance I dispose the engine-cylinders radially, and have for the primary object of my invention to so construct and support a pair of cylinders as 25 to form practically an engine section, whereby any number of such sections may be readily and conveniently coupled together to provide an engine with the required amount 30 of power.

A further object of my invention is to provide a multiple cylinder engine for motor vehicles which is simple and compact in construction, occupies a minimum of 35 space, and is also effective in operation.

Other objects and advantages of my invention will hereinafter appear, and what I claim as new, and desire to secure by Letters-Patent, is more specifically set forth in 40 the appended claims.

In the accompanying drawings, which form a part of this specification: Figure 1 is a front elevation of an internal combustion engine constructed in accordance with 45 my invention and including two pairs of cylinders or engine sections. Fig. 2 is a plan view, the engine being slightly turned with reference to Fig. 1. Fig. 3 is a vertical sectional view through one of the engine 50 sections. Fig. 4 is a detail view of the connected pistons of one of the engine sections. Fig. 5 is a detail sectional view on the line 5—5 of Fig. 1. Fig. 6 is a front elevation, partly in section, of the casting or frame of 55 an engine section. Fig. 7 is a vertical transverse sectional view thereof. Figs. 8 and 9

are detail views of a plate which is attached to the front of the engine frame or casting.

Like numerals of reference indicate like parts in all the figures of the drawings.

In carrying out my invention I provide 60 an engine section or unit comprising a circular supporting-frame, a pair of radially disposed engine-cylinders, operating connections for said engine-cylinders, and a crank-shaft to which the pistons are connected, all as hereinafter particularly described.

The supporting frame of the engine-section is, in the present instance, made of a 70 single casting and consists of an outer ring or rim 10, having inwardly-projecting reinforcing side flanges 10^a, 10^b, an inner ring 11, and vertical and horizontal webs 12 and 13, respectively, connecting said 75 rings, the inner ring being closed at one side by a wall 14 in which is formed one of the bearings, as 15, for the crank-shaft 16 of the engine. Also formed integrally with this supporting-frame or casting are two 80 cylindrical casings or jackets, 17 and 18, to receive the engine-cylinders, hereinafter described, said casings or jackets being disposed radially and on a line with each other.

Within each cylindrical casing or jacket 85 is mounted an engine-cylinder 19, secured in place in any suitable manner, for instance by ordinary screw-threads, as at 19^a, and each cylinder is provided with a head 20, offset at one side to provide for the usual intake valve 21 and exhaust-valve 22, said valves being closed automatically by springs 23 and 24, respectively, and the stem 25 of the exhaust-valve extended and provided with an anti-friction roller 26 engaged by a 90 cam 27 on a shaft 28, for mechanically opening said valve. In the present instance the intake valve 21 is opened to charge the cylinder by suction on the outstroke of the piston, but of course said intake valve may be 100 also opened mechanically in like manner as the exhaust-valve. The cam-shaft 28 is driven from the crank-shaft 16 by a suitable train of gearing (indicated in dotted lines in Fig. 1), and it will be noted that 105 the aforesaid cam-shaft is mounted in bearings formed on the horizontal connecting webs 13 of the supporting-frame, and that a cam-shaft is provided for the exhaust-valve of each engine-cylinder. It will be noted, 110 also, that the bearings 30, 30, for the idle-wheels of the two trains of gearing are on a

face-plate 31, which is attached to the front of the supporting-frame by screws 32, and that the bearing, as 33, for the crank-shaft is also formed on said face-plate.

- 5 For the purpose of maintaining either one or both of the exhaust-valves of the engine open, to thereby permit the engine to run free without drawing in any gasolene or explosive-mixture, I provide a slide 34
 10 for each of said valves, said slide having a keyhole slot 35 (see Fig. 5) through the larger portion of which a collar 36 on the valve-stem normally works. Now when the slide is shifted to the position shown in said
 15 Fig. 5 the smaller portion of the slot takes the stem 25 and the end of the collar abuts against the slide, thereby holding the exhaust-valve open against the action of its closing spring. Each slide 34 is supported
 20 on a boss 37 on the engine frame, being connected thereto by a screw 38 passing through a slot 39 in said slide, the latter having an arm 34a by which it is connected to a sliding-rod 40; it being understood that
 25 when two engine sections are connected, as illustrated in Figs. 1 and 2, each operating rod 40 is of such length as to operate two slides, and when three engine sections are coupled the rod is of a length to operate
 30 three slides, and so on. Likewise, when two or more engine-sections are coupled together the crank-shaft and valve-operating cam-shafts are of proper lengths to correspond, and of course the cranks 45 on the
 35 crank-shaft disposed so as to apply the power to said shaft from the pistons in succession.

The cylinders of each engine-section are disposed radially on a line with each other, 40 and the pistons, 41, 41, working in these cylinders are connected to operate in unison by a tubular member 42, the attachment of the pistons to said connecting member being made in the present instance by threading
 45 the reduced inner ends of said pistons into the enlarged outer ends of the tubular member, as shown in the drawings. The tubular connecting-member is provided with opposite slots 43, for the accommodation of
 50 the crank-shaft 16, and the outer end of the crank 45, located within said tubular member, work through slots 44, the latter being of such length as to accommodate the link or piston-rod 46. The piston-rod is con-
 55 nected to one of the pistons, or to one end of the tubular connecting member, by a pin 47; and, of course, inasmuch as the pistons are connected but a single link or piston-rod is required. The cranks and piston-rod con-
 60 nections may be of any approved type, and suitable means provided for supplying the bearings with oil. Furthermore, the heads of the cylinders, and valves therein are of the usual type, the head being provided with
 65 plugs or threaded caps 48, to give access to

the valves, and with inlet and exhaust pipes, 49 and 50, respectively, leading to and from said valves, as will be understood.

To the supporting-frame of each engine-section are bolted or otherwise attached angle-plates 51, 51, for convenience in mounting the engine on the chassis of an automobile or supporting frame of any other type of motor vehicle.

By reference to Figs. 1 and 2 of the drawings it will be noted that in order to provide an engine of four cylinders two of the engine sections or units are arranged side by side and bolted together by passing bolts, as 52, through the connecting webs 12 and 13, as indicated in Fig. 3, and in this instance the closed walls 14, 14, of the two sections are brought together and face-plates 31 applied to the outer sides of the connected sections, as shown in Fig. 2. When thus connected the two pairs of engine-cylinders are disposed in the form of an X. Of course if a third pair of cylinders is desired a third engine-section would be bolted to one side of the other two, the face-plate at that side being removed so that the additional section may be brought close against the adjoining one; and in this instance the cylinders of the added engine-section would be disposed on a line with the cylinders of one of the other engine-sections. Similarly a fourth engine-section could be coupled, and so on, and of course in each instance a crank-shaft having the proper number and disposition of cranks, and cam-shaft having the proper number and disposition of cams, would be supplied, corresponding with the number of cylinders to the engine. By this arrangement, or thus constructing an engine-section, an engine having any number of cylinders may be readily and conveniently built up to suit requirements.

The operation of the engine is similar to that of the conventional type of internal combustion engines, provision being made in the present instance to save the consumption of gasolene or other hydrocarbon used for driving the engine by simply shifting the slides 34 so as to hold the exhaust-valves open and allow the several engine-cylinders to draw in air through the exhaust pipes. Any suitable means may be provided for operating the rods 40 connected to said slides.

Having described my invention, I claim:

1. An engine section or unit, comprising a circular supporting frame having inner and outer rings, cylinder-jackets extending radially between the rings and formed integrally therewith, engine-cylinders removably mounted in the aforesaid jackets and having pistons therein, bearings in the frame, operating shafts and a crank-shaft mounted in the bearings, the crank-shaft being connected to the pistons, and inlet and exhaust valves for the engine-cylinders.

2. An engine section or unit, comprising a circular supporting frame having inner and outer rings, webs connecting said rings at opposite sides of the frame, and a wall 5 closing one side of the inner ring; a removable plate for closing the other side of said inner ring, bearings in the webs and removable plate, and cylindrical jackets extending radially between the rings and formed integrally therewith; together with engine-cylinders removably mounted in the jackets, pistons in the engine-cylinders, a crank-shaft mounted in one set of bearings and connected to said pistons, inlet and exhaust 10 valves for the engine-cylinders, and operating shafts for the engine mounted in the webs and removable plate.
3. An engine section or unit, comprising a cast frame composed of inner and outer 15 rings, webs connecting said rings at opposite sides of the frame on a plane with the
- outer edges of the rings, cylindrical jackets extending between the rings and formed integrally therewith, a wall closing one side of the inner ring on a plane with the adjacent webs and edges of the rings, and a removable plate for closing the other side of the inner ring, the webs of the cast frame having holes providing means for attaching one section or unit to another; together with 20 supporting flanges on the outer circumference of the cast frame, engine cylinders mounted in the jackets, and valves and operating shafts for the engine.
- In testimony whereof I have signed my name to this specification in the presence of two subscribing witnesses.

GIDEON R. IBACH.
